UNITED STATES PATENT OFFICE.

FRED FRANCIS FLAGG AND GEORGE W. SMITH, OF WORCESTER, MASSACHUSETTS, ASSIGNEES
TO JOHN A. SHERMAN, OF WORCESTER, MASSACHUSETTS.

ENVELOP-MACHINE.

No. 902,222.

Specification of Letters Patent.

Patented Oct. 27, 1908.

Application filed May 4, 1907. Serial No. 371,777.

To all whom it may concern:

Be it known that we, FRED F. FLAGG and GEORGE W. SMITH, both of Worcester, in the county of Worcester and State of Massachusetts, and both citizens of the United States, have invented a new and useful Improvement in Envelop-Machines, of which the following is a specification.

In Letters Patent of the United States No. 843,707, dated February 12, 1907, and granted to John A. Sherman, there is described a plunger used in connection with a creasing table and folding box of an envelop machine of a type well known. The plunger has an opening surrounded by a casing which forms a hopper for a pile of transparent blanks or patches, the patches being kept from falling through the opening by clips arranged around the edge of the opening. The patches are intended to be attached to an envelop having an opening in its face, the edges of the opening being gummed, the patch closing the opening, and by reason of its transparent character allowing the address upon the inclosure to be read, so saving the trouble of addressing the envelop.

Our invention consists in means for centering and supporting patches of a similar character in the plunger so that the lower patch of the pile which comes in contact with and is to be attached to the envelop blank about to be folded will be the more easily attached and withdrawn from the bottom of the pile while the rest of the patches will be properly supported within the casing, and also in a carrier constructed to coöperate with such a plunger without reducing the speed of the machine.

Our invention will be understood by reference to the drawings, in which—

Figure 1 is a top view of a plunger embodying our invention, Fig. 2 being an under view thereof, Fig. 3 an end view, a portion of the edge being broken away to show the construction of one of the posts. Fig. 4 is a sectional elevation on line 4—4 of Fig. 1, and Fig. 5 is a plan of the open envelop blank with patch attached. Fig. 6 is a view corresponding to Fig. 1 but showing a patch of different shape. Fig. 7 is a plan of our carrier in its forward position. Fig. 8 is a plan of our carrier in its rearward position, and Fig. 9 is a longitudinal section on line 9—9 of Fig. 8.

The plunger A is operated in the usual manner. It is rectangular and of any ordinary outline to conform to the shape of the envelop and to the opening A¹ in the creasing frame by means of which and the plunger 61 the envelop blank is to be creased.

A² is the plunger rod from which the plunger is hung. This plunger is provided with a feed opening A³. Vertical rods B, B¹ are mounted near each end of the opening 65 and to the bottom of each rod is attached a clip b to form a support for the pile of patches C contained above it. The rods B, B¹ serve as guides to keep the blanks properly piled and in proper place to be fed and also to 70 engage the patch and assist in holding the patches in the plunger.

The preferred shape of the patches is shown in Fig. 5 where the patch is lettered C¹ and it is there shown attached to the inner surface of the envelop blank D. The patch is approximately rectangular and of sufficient size to close the opening in the envelop. Near each end it is narrowed as at c and at each end it is provided with ears c¹ 80 thus forming notches which fit around the rods B, B¹ (or around the rods B² in the modification below referred to), engaging them more or less closely and coöperating with these rods to hold the patch from 85 endwise movement. This is a convenient way of holding the ends of the patches from longitudinal movement. Thus the pile of patches is properly supported at each end, while there will be a tendency to sag 90 at the middle on the part of the lower patches of the pile. The patches, however, cannot fall out because of the engagement of the ears c¹ with the rods B, B¹.

As the plunger moves downwardly upon 95 an envelop blank the middle or sagging portion of the lower patch (see Fig. 4) strikes the gummed surface on the envelop blank first, and as the plunger rises the lower patch by reason of its engagement with the blank 100 is drawn out from the plunger, the ears c¹ being drawn out from behind the rods B, B¹. The patch is then pressed in place by the pressure of the folders as they fold the envelop. These folders are indicated at E and are operated in the usual way, the bottom of the box being lettered E¹. We prefer to make two of these rods adjustable in order to conform to any possible irregularity in the cutting of the patches. For this purpose 110

instead of being fixedly supported in the plunger the rods B^1 are supported in grooves b^1 in the walls of the plunger opening and set screws b^2 are provided which pass through 5 the edge of the plunger, the end of each screw being attached to its rod B^1 so that as the screw is turned the foot of the rod is moved either in or out as the case may be. The heads of the screws should not project 10 beyond the outer wall of the plunger, otherwise they will strike the walls of the creasing frame.

While we have shown four rods forming a skeleton inclosure for the blank pile, it is 15 evident that a casing may be provided instead the walls of which are so shaped as to engage ears c^1 or their equivalents, and it is also evident that the opening of the plunger may be of any convenient shape provided 20 clips such as are shown at b are mounted on the plunger to support the blanks, and means are provided to engage the edges of the blanks and hold them from endwise movement as described. For example, we have 25 shown in Fig. 6 another construction wherein the patches though differently shaped are similarly held. In this construction there are but two rods which we have lettered B^2 , each carrying clips b , and in this case the ears c^2 on the patches turn inwardly instead of outwardly so that each pair of ears hug around the same rod B . The rods in this case are approximately of the same shape as the space between the ears. The principle of 30 operation in each case is the same in that the blanks are held from falling downward by clips and from endwise motion by rods past which, however, they may slide or be pulled as occasion requires, the pile of patches in 35 each case being pressed back into their normal or proper position by the pressure of the plunger on the bottom of the folding box each time the plunger strikes the envelop blank. The improvement in the carrier 40 which renders it possible to use this mechanism without interfering with the speed of the machine is shown in Figs. 7, 8 and 9. In each case F represents the ways in which the carrier is caused to slide by means such 45 as is usual in such cases. These ways are provided with cross-bars F^1 , F^2 , which together with the portion of the ways lying between them form the creasing frame, this being the usual construction in every respect 50 except that the cross-bar F^2 has a slight elevation f for purposes to be hereinafter described.

The carrier G performs the usual function of carrying the blank from the picker to the plunger. Its forward end g^1 is cut away at 55 g^2 so as not to engage with the rising picker as it moves forward. It is mounted as usual on slide-bars g and is operated in the usual way. Instead of the usual construction of that part of the carrier which supports the

back flap of the envelop, we provide swinging wings each comprising two arms H , H^1 , each wing being pivoted in a slide-bar g at H^2 . The arms H support the back flap end of the blank and the arms H^1 engage 70 with pins h on the ways F , F to spread the wings against the stops h^2 as the cam moves rearward towards the creaser frame and with pins h^1 , h^1 mounted on rods h^2 , h^2 at the forward end of the ways F , F to close the 75 wings again so that they may be in position to receive a fresh blank. For this purpose the arms H^1 are preferably made wedge-shaped. By this means a clear passage is allowed so that the carrier can start forward 80 before the plunger clears the creasing frame in its upward movement.

It is evident that the wings may be spread by engagement of the parts H with the bars B , B as the carrier moves forward without 85 the intervention of the pins h , h , but we prefer to provide especial means for the purpose as shown. We have provided the cross-bar F^2 with the elevation f^1 and have bent the arms H , H to ride over this elevation as 90 shown in Fig. 9, as this brings the gummed surface to which the patch is to be attached into a higher position for engagement with the patch as the plunger in its descent will strike that portion of the blank first and 95 cause the engagement of the patch with it.

It is evident that the shape of the wings may be changed and different means be adopted for moving them. So far as we know the use of a carrier having a movable 100 part or parts for supporting a portion of the blank from below is entirely new with us and it has added materially to the speed of the machine.

The advantage of our improvement over 105 the invention shown in the patent above referred to lies mainly in the fact that the patches are held near the corners so that the middle portion of the lower patch is free to engage with the gummed surface of the envelop blank, and when engaged will pull the ends of the blank from their retaining means, and the retaining means may be any means which will support the ends of the blank from falling out of the plunger while 110 allowing the middle portion to sag and strike the gummed surface of the blank in advance of the rest of the patch.

What we claim as our invention is:

1. In an envelop machine, a plunger having a feed opening therein, and means located about said opening for holding the ends of patches correspondingly shaped and supported above said opening from a movement towards each other. 120

2. A plunger having an opening therethrough the edge of which is provided with projections forming with the ends of said opening recesses near said ends, rods located on said projections and projecting upwardly 125 130

therefrom whereby blanks shaped suitably to said opening will be restrained from movement towards the middle of said opening, and means to prevent the dropping of such blanks down through said opening, as described.

3. In an envelop machine, a plunger having a feed opening narrower near the end than at the middle, the narrowing edges of the opening being adapted to engage corresponding portions of the patches corresponding in shapes to said opening and hold them from movement towards or from each other.

15 4. In an envelop machine, a plunger having a feed opening substantially rectangular in shape, having near each end a narrowed portion and at the extreme end a wider portion, whereby a blank correspondingly shaped may be held from lengthwise movement by engagement of its end sections with the narrowed portion of said opening.

25 5. In an envelop machine, a plunger having a feed opening substantially rectangular in shape provided near each end with guide rods projecting into and narrowing the feed opening, whereby the ends of the lower one of a pile of blanks held above said opening shaped to correspond therewith are kept 30 from movement towards or from each other and the lower blank is allowed to sag at the middle, as and for the purposes set forth.

6. In an envelop machine, a plunger having a feed opening and means for holding 35 a stack of patches therein comprising rods located in pairs, one pair at each end of said opening, the rods of each pair being nearer together than the main width of the opening whereby said rods may coöperate 40 with the lateral edges of a suitably-shaped patch to hold it in place, as set forth.

7. In an envelop machine, a plunger having a feed opening and means for holding a stack of suitably shaped patches therein 45 comprising rods located in pairs approximately at the corners of said opening, one rod of each pair being adjustable towards and from the other rod of the same pair whereby said rods may be caused to engage 50 with side edges of said patches, as set forth.

8. In an envelop machine, a plunger adapted to be reciprocated to crease an envelop blank, having a feed opening and means such as vertical rods for holding suitably 55 shaped patches therein at approximately the four corners thereof, whereby the lower blank will sag midway between its ends, but said ends will be held from movement towards each other, in combination with a 60 folding box located below said plunger and adapted to coöperate with the plunger and envelop blank to withdraw a patch from the feed opening.

9. In an envelop machine, a plunger having a feed opening therein, a plurality of

carrying clips and bars, each bar forming a recess between it and the nearer end of said opening whereby it may engage with a notch in the patch to be carried by said plunger over said feed opening and prevent said patches from movement toward the center thereof.

10. In an envelop machine, in combination with a plunger, a carrier having movable wings adapted to support the blank upon said carrier during the rearward movement thereof, and means located at the extremity of its rearward line of movement whereby said wings will be spread to allow the carrier to pass said plunger on its return movement while said plunger is below the level of said carrier.

11. In an envelop machine, in combination with a plunger, and carrier ways, a carrier having movable wings, said wings being substantially angular in shape, and means mounted upon the carrier ways to throw said wings into blank-holding position while said carrier is in its forward position, as described.

12. In an envelop machine, a plunger, ways to support a carrier, a carrier adapted to run in said ways and having wings angular in shape, and means located at each end of said ways to engage said wings and cause them to spread and also to close in to form a support for the blank, as set forth.

13. In an envelop machine, in combination, a plunger provided with a feed opening, means for supporting patches within said feed opening, a carrier located to move across the path of said plunger, a creasing frame adapted to cooperate with said plunger to crease the envelop blank, the rearward wall of said creasing frame being elevated whereby one edge of the blank will be elevated and the plunger will strike the elevated edge of the blank first in its descent.

14. In an envelop machine, a plunger having a feed opening, means for holding a pile of patches therein, a carrier adapted to carry a blank under said plunger, a creasing frame located below said plunger and adapted to coöperate therewith to crease the blank and remove it from the carrier, the wall of said creasing frame adjacent to the feed opening in said plunger being slightly elevated whereby the plunger in its descent will cause a patch to first strike the blank at a point near the creasing frame, as set forth.

15. In an envelop machine, a carrier having a horizontal movement and adapted to cooperate with a vertically moving picker by means of which the blanks are to be 125 gummed and deposited upon the carrier, being substantially rectangular in shape with, however, a portion projecting forward adapted to support one of the wings of the envelop blank and said carrier being cut 130

- away at its front edge whereby in its movement in a direction toward the picker it may partially overlap the path of the picker, as described.
16. In an envelop machine, a creasing frame one side of which is elevated, a carrier adapted to move over the creasing frame, said carrier being provided with wings adapted to support a portion of the blank, the supporting arms of said wings being angular in shape to ride over said elevation.
17. In an envelop machine, a plunger, a carrier and a creasing frame, and means whereby one side of the blank carried on said carrier is held in position to be struck by said plunger in its descent before the plunger strikes the other side thereof.

FRED FRANCIS FLAGG.
GEORGE W. SMITH.
